OTTO KURZ AND CHARLES KURZ, OF NEW YORK, N. Y.

ELECTRIC LAMP.

1,303,832.

Specification of Letters Patent. Patented May 13, 1919.

Application filed April 1, 1918. Serial No. 225,931.

To all whom it may concern:

Be it known that we, OTTO KURZ and CHARLES KURZ, both citizens of the United States of America, residing at New York 5 city, Bronx county, State of New York, have invented certain new and useful Improvements in Electric Lamps, of which the following is a full, clear, and exact description.

This invention relates to improvements in 10 electric lamps, more especially that class known as spot or search lights with which motor vehicles are usually provided. One of the objects of our invention is to provide a search or spotlight arranged for use as a 15 trouble light; in other words, for use about the machine, should engine, tire or other troubles occur. To carry our invention into practice, we have designed a special mechanism organized to adapt the light for use as 20 a spot or search-light, in which event it will be attached to a suitable bracket carried by the vehicle (the windshield structure for instance) or as a trouble-light, in which event it will be detached from its bracket and carried 25 to that point where the trouble exists. To adapt the light for the latter purpose, we have arranged a normally coiled-up cable which may be unwound when the light is detached from its bracket and carried away 30 therefrom. Other features of improvement will hereinafter appear.

We will now proceed to describe our invention in detail, the novel features of which we will point out in the appended claims, 35 reference being had to the accompanying drawing, wherein:—

Figure 1 is a central sectional view of our improved lamp, the section being taken on a line 1—1 in Fig. 2;

Fig. 2 is an end view thereof looking from the left in Fig. 1;

Fig. 3 is an end view of the cable-reel which also carries the circuit-contacts; and

Fig. 4 is an enlarged fragmentary sectional view illustrating a portion of the cable-reel, lamp casing and retaining-ring for the reel.

As herein embodied, our improved lamp consists of a casing 5 carrying at one end 50 thereof a reflector 6 and a lens 7, said reflector and lens being held in place by a retaining ring 8. The remainder of the interior of the casing 5 houses a rotatable drum or reel 9 which supports a lamp socket 10, said socket projecting through an opening 11 in the reflector 6. The socket in this

instance is supported by or attached to an annular flange 12 carried by the rear plate 13 of the reel. The forward portion of the socket 10 is supported by the front plate 14 of said reel. The numeral 15 indicates the drum portion of the reel about which a conducting cable 16 is wound, said cable containing two conductors 17 and 18, Fig. 3. For the purpose of rotatably supporting the reel, the rear wall 13 thereof is extended beyond the drum 15 and terminates in an annular flange 19 (see Fig. 4) to which the annular flange 20 of a rotatable ring 21 is fitted; in other words, the ring 21 fits over the flange 19 of the reel 9. As can be seen in Figs. 1 and 4, the ring 21 and adjacent portion of the lamp casing 5 are of equal diameter, the adjacent ends thereof being in contact but unsecured one to the other. To retain the ring 21 and casing in the aforesaid relationship, one to the other, we provide a retaining ring 22, which is secured to the lamp casing by screws 23. Although the reel 9 and rotatable ring 21 are both free from the casing, they are connected together by screws 24 (Fig. 1) and hence will rotate in unison.

As can be seen in Fig. 2, the rotatable ring 21 is provided with an opening 25 covered by a mirror 26 mounted on the inside surface of the plate portion of the ring (see Fig. 1). The mirror 26 is a mirrorscope for use in daylight to enable the driver of a motor vehicle to observe those in the rear. It will be apparent that when the ring 21 is rotated the reel 9 will also be rotated, end movement on the part of the ring and reel being prevented by the casing 5 and retaining ring 22 attached thereto. The retaining ring 22 acts as a bearing member to rotatably support the ring 21 and reel attached thereto. To rotate the ring 21 and cable reel, we provide said ring with a handle 27 which houses a slidible push-button 28. The function of the push-button is to complete or break the circuit for a lamp (not shown) carried by the socket 10.

The circuit for the lamp includes contacts 28 and 29 (Fig. 3) carried by a block 30 of insulating material mounted on the rear plate 13 of the reel 9, and a circuit-closer 31, also mounted on said block 30. The contacts 28 and 29 will each be connected to their respective conductor 32 and 33 of the socket 10. One of the cable conductors 18 will be connected to the contact 29, the other

cable conductor being connected to the circuit-closer 31. As can be seen in Fig. 1, the circuit-closer 31 extends to a point in line with the push-button 28^a and hence is operated to close or break the circuit by said push-button. When the switch 31 is pushed in, the circuit will be broken. When the push-button is pulled out, the circuit will be complete, as the circuit-closer 31 will, at 10 such a time, contact with the finger 31^a of the contact 28 which overhangs said circuit-closer.

As is evident from an inspection of Fig. 1, the cable 16 is or may be wound around 15 the reel 9, the free end thereof being passed through an opening 33 in the casing, thence through a hollow or tubular post 34 which carries ears 35 pivotally connected to a bracket 36 carried by the casing 5. The 20 pivotal connection referred to permits the casing to be adjusted in a vertical plane. When connected to a vehicle, the post 34 will rotatably engage a suitable bracket 37 and hence can be adjusted in a horizontal 25 plane and held in an adjusted position by a binding screw 38. The free end of the cable 16 will be suitably connected with a source of electrical energy (not shown).

As a further feature of improvement, we 30 provide the casing with a supplemental forked support 39 adjustably held by a bracket 40 having a binding-screw 41. When connected to the bracket 37, the lamp 35 will be used for spot or search-light purposes; at such a time the cable will be coiled or wound upon the reel 9.

To use the lamp in connection with engine, tire or other troubles, it will be removed from the bracket 37 and carried to 40 the desired place. During the transporting of the lamp, the cable 16 will unwind, it being unnecessary to break the connection between the cable and source of electrical supply. The cable 16 will be long enough to 45 permit the lamp to be carried to any part of the vehicle. Should it be necessary to rest the lamp upon a running board, mud-guard or the ground, the post 34 and forked support 39 can be used as a tripod or stand 50 to support the lamp. Any angle of adjustment can be obtained by merely adjusting the post 34 and forked support 39, the binding-screw 41 and screw 42 (Fig. 2) on the bracket 36 being used to hold the post and 55 standard in the adjusted positions.

When the lamp is to be again restored to the bracket 37, the cable 16 will be rewound upon the reel by rotating said reel by means of the handle 27. It will be, of course, 60 understood that a light will be produced when

desired by manipulating the push-button 28^a.

What we claim as our invention is:

1. In an electric lamp, a rotatable reel, a lamp-socket carried thereby, a conducting cable in circuit with said socket, said cable being wound upon said reel, a handle connected with said reel, a circuit-closer, and means carried by said handle, to operate the circuit-closer. 65

2. In an electric lamp, a casing, a rotatable reel within the casing, a lamp socket carried thereby and rotatable therewith, contacts carried by the reel electrically connected with the conductors of said socket, a circuit-closer adjacent one of said contacts, means to operate said circuit-closer, a conductor connected to one of said contacts, and another conductor connected to said circuit-closer, said conductors being wound around 80 said reel. 70

3. In an electric lamp, a casing, a rotatable reel within the casing, a lamp socket carried thereby and rotatable therewith, contacts carried by the reel electrically connected with the conductors of said socket, a circuit-closer adjacent one of said contacts, means to operate said circuit-closer, a conductor connected to one of said contacts, another conductor connected to said circuit-closer, said conductors being wound around 85 said reel, and a non-rotatable reflector adjacent said socket. 90

4. In a motor-vehicle spot-light, a rotatable reel, a rotatable ring secured thereto, a casing, means to rotatably secure the said ring to said casing, a socket carried by the rotatable reel, contacts located centrally of the reel in circuit with the conductors of the socket, a circuit-closer adjacent one of said contacts, the free end of said circuit-closer extending to a point adjacent the periphery of said reel, means carried by the support for said reel arranged to move the circuit-closer in and out of contact with its adjacent socket contact, a flexible conductor connected to said circuit-closer, and another flexible conductor connected to the socket contact on the side of the circuit opposite to the adjacent side in which the contact adjacent the circuit-closer is included, said flexible conductors being wound around said rotatable reel. 100

Signed at New York city, N. Y., this 30 day of March, 1918.
